Attorney

UNITED STATES PATENT OFFICE.

GEORGE G. BABICH, OF NEW YORK, N. Y.

COFFIN-BOX.

1,259,068.

Specification of Letters Patent. Patented Mar. 12, 1918.

Application filed October 20, 1916, Serial No. 126,676. Renewed July 31, 1917. Serial No. 183,760.

To all whom it may concern:

Be it known that I, GEORGE G. BABICH, a citizen of the United States, residing at New York, in the county and State of New York, have invented certain new and useful Improvements in Coffin-Boxes, of which the following, is a full, clear, and exact specification.

This invention relates to coffin boxes, and has for its object to provide an improved metal inclosure for caskets especially adapted for use when the casket is to be inclosed in a plastic casing, such as is disclosed in my Patent No. 1,153,535, issued September 14, 1915, but which may also be advantageously employed for incasing any casket for burial. A special object is to provide a metallic casing which will preserve the casket from contact with the plastic material of the outer casing disclosed in the above mentioned patent or with any other surrounding material. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a detailed plan view of the metal coffin box.

Fig. 2 is a longitudinal vertical section on the line II—II of Fig. 1.

Fig. 3 is a front end elevation showing the closure partly raised, and

Fig. 4 is a transverse vertical section on the line IV—IV of Fig. 1.

The metal coffin box 23, is preferably made up of a plurality of transverse sections 230 having their edges overlapped, as at 37, and forming the sides and top of the coffin box. The bottom 38 of said coffin box is made in a single piece, and the ends of the transverse sections 230 are secured to the edges of the bottom piece 38 by solder or strips 39 making a water tight joint. The overlapping edges of the transverse sections 230 are cov-

ered by bands or strips 24 which also make water tight joints between them.

One end 40 of the coffin box is permanently closed and sealed, while the other end 55 is provided with a removable closure 27 adapted to slide in grooves 26 formed in the side walls of the coffin box, as clearly illustrated in Figs. 1, 2 and 3. The lower edge of the closure 27 is adapted to fit in a groove 60 formed by the flange 25 at the bottom of the other end of the coffin box. The upper edge of the closure 27 is provided with a turned over flange 28 which serves as a handle for moving the closure into and out of position. 65 After the coffin has been placed in the coffin box, the closure may be soldered or otherwise sealed in closed position.

By making the sides and top of the coffin box in transverse sections with overlapping 70 edges covered by the bands 24, the structure is made very strong and capable of resisting the pressure of the concrete which is placed around it when used with the plastic outer casing, shown in my patent hereinbefore mentioned. This rugged construction of the coffin box also renders it capable of resisting considerable outside pressure of earth when used without the plastic outer casing. Each of the bands 24 is stepped, as 75 clearly shown in Fig. 2, to fit the overlapped edges of the sections 230. The thicker portions of said bands engage the underlapped sections, while the thinner portions of said bands engage the overlapped sections, thereby sealing the lapped joints and reinforcing the sides and top of the coffin box. 85

Having thus described my invention, what I claim as new and desire to secure by Letters Patent of the United States is:

1. A metal coffin box consisting of a bottom, transverse sections forming the sides and top of the box and having their ends secured to the bottom and their edges overlapped upon one another, bands covering 95 the overlapped edges of said transverse sections, each of said bands being stepped to fit said overlapped edges, the thicker portions of the bands engaging the underlapped sections and the thinner portions thereof 100 engaging the overlapped sections.

2. A metal coffin box having an upwardly

turned flange at one end of its bottom and grooves formed in the sides at the same end, a top terminating short of the plane of said grooves and a closure adapted to slide in said grooves and have its lower edge engage the flange on the bottom, said closure having a turned over horizontal flange at its

upper edge adapted to overlap and lie flat on the top of the coffin box when closed, whereby said closure may be readily soldered all around to the coffin box.

In testimony whereof I have signed my name to this specification.

GEORGE G. BABICH.
